WORK GUIDE FOR SEWING MACHINES

William D. Harrod, Greensboro, N. C., assignor to
Union Special Machine Company, Chicago, Ill.,
a corporation of Illinois

Application April 24, 1951, Serial No. 222,627

8 Claims. (Cl. 112—20)

2

This invention relates to work guides for sewing machines and more particularly to uncurler guides used in connection with cup feed machines employed in the seaming of hosiery.

It has been found that in the use of uncurler guides as heretofore constructed, for uncurling the edges of a hosiery blank and delivering the same to the feed cups, one or both of the selvage edges of the blank has frequently been caught in the openings provided in the clamping boots of the device for cooperating with a guide pin carried by the central support member. This has been due to the tendency of the selvage edges to curl outwardly again as they pass the openings. So also in cases in which the knitter has left a free end of knitting thread at the selvage edge this has become caught between the guide pin and the edge of the opening in one of the boots. In either event the proper feeding of the work is interfered with and pleats are produced in the seam and the heels or other parts of the blank have had their edges mis-matched. Difficulty has also been encountered in keeping the work properly in the guide. These difficulties have been particularly encountered in the seaming of the heel portions of the blank because the edges are held somewhat higher in the guide in the sewing of this part of the stocking in order to form a deeper overedge seam.

A primary object of the present invention has been to provide an uncurler guide which is free of the difficulties explained above and which will present the selvage edges of hosiery blanks and the like to the feed cups of the machine in a way to insure uniform seam formation.

Another object has been to provide an uncurler guide which performs two uncurling actions upon the edges of the blank being fed to the cups to insure proper presentation of the edges, in flattened condition and without pulling or pleating, to the stitch forming devices. The main uncurling action is performed in the conventional manner as the selvage edges are drawn into the passage between the inner faces of a pair of sprung urged boot members and the opposed faces of a stationary guide blade, while a second uncurling action takes place just beyond the guide pin and quite close to the point of delivery of the flattened edges to the feed cups. This second uncurling action offsets the temporary outward curling of the edges which takes place at the openings in the boot elements. As an incident to this second uncurling action the blank is retained by the guide in proper position for presentation to the feed cups and the stitch forming devices. The

tendency of the blank to drop out is counteracted by the retaining effect of certain uncurling projections.

Other objects, features, and advantages of the invention will appear from the detailed description of an illustrative embodiment of the same which will now be given in conjunction with the accompanying drawings, in which:

10 Fig. 1 is a front elevational view of the upper left hand portion of a cup feed sewing machine embodying the invention;

Fig. 2 is a detail view along the line 2—2 of Fig. 1, in side elevation as viewed from the left in Fig. 1, of the lower portion of the uncurler

Fig. 3 is a view of the parts shown in Fig. 2 as seen from the left in Fig. 2:

Fig. 4 is a detail view, in side elevation, of one of the boot elements forming part of the uncurler 20 guide.

Fig. 5 is a bottom view of the uncurler guide; Fig. 6 is a view showing a hosiery blank, par-

25 Fig. 7 is a horizontal sectional view along the line 7-7 of Fig. 6.

Referring now to the drawings, the invention has been illustrated as applied to a cup feed sewing machine.

has been illustrated as applied to a cupped sewing machine of the general type illustrated in the Rubel, et al. Patent No. 2,043,711, granted June 9, 1936, or in the Hacklander Patent No. 2,043,748 granted June 9, 1936. Since the invention

2,043,448, granted June 9, 1936. Since the invention relates to the uncurler guide and means co-operating with it, only those portions of the machine are illustrated and will be described. It will be understood that the parts of the machine which are not illustrated or described may suitably be of the character shown in either the Rubel, et al. patent or the Highlander patent mentioned above.

40 The machine has a frame adapted to enclose the operating mechanism in a lubricant tight housing, this frame comprising a vertical standard portion 10 (Fig. 1) and a laterally projecting head or bracket arm 11. The latter carries a pair of depending shafts 12 and 13 which carry, respectively, the two feed cups 14 and 15. These are driven step by step upon operation of the

machine through mechanism of the character disclosed in the patents above mentioned. It will be understood that the shaft 12 carrying the outer feed cup is adapted to be swung outwardly to facilitate the introduction of work. The stitch forming devices are only partially disclosed. They include a needle bar 16 mounted for recip-

rotation in a bearing sleeve 17 and carrying at its outer end a needle 16a (Fig. 7). A thread carrying looper is mounted for both reciprocation and oscillation in a bearing sleeve 18 while a spreader is mounted for oscillation only on a shaft 19 journaled in a bearing sleeve 20. It will be understood that these stitch forming elements are operated in coordination to produce a two thread overedge stitch just above the upper edges of the rims of the feed cups 14 and 15, substantially at the bight of the cups.

The uncurler guide is carried by a head 21 suitably secured by a screw 21a to the end of a sleeve (not shown) journaled in a horizontally disposed bearing 22 carried by the arm 11 of the frame. The arrangement is such that the head 21, with its connected sleeve, may be rotated through an angle of about 90° to place the uncurler guide either in its operative position shown in Fig. 1 or in an inoperative position in which it extends forwardly from the bearing 22. It may also be held in an intermediate loading position. Suitable means are provided for swinging the guide structure and for retaining it in any of the three positions indicated. These means may suitably be of the character disclosed in the patent to Hacklander No. 2,131,007, granted September 20, 1938, or in the patent to Kucera No. 2,292,762, granted August 11, 1942. It includes a lever 23 having a finger portion 23a at its outer end and secured to a shaft 24 which extends through the sleeve on which the head 21 is mounted. For further details as to the construction and operation of the detent or locking means, reference may be had to said Kucera patent.

A plate-like support member 25 is secured by screws 26 to a radially extending portion 21b of the head 21. Plate 25 is preferably provided with laterally elongated openings to permit slight adjustment of the plate in relation to the head. A rib 25a formed on the plate cooperates with a groove in the part 21b of the head. At the lower end of the plate there is secured a relatively thin blade 27 which may be fastened to the plate by welding or riveting or the like. Blade 27 preferably has the configuration indicated in Fig. 2 and serves as a stationary guide against the opposite faces of which the two edges of the blank to be stitched are held and along which they are drawn. Just above the blade 27 the plate 25 has a pair of laterally extending arms 28 which provide bearings for pivot pins 29 and 30 carried, respectively, by hinge portions of presser members 31 and 32. Screws 33 and 34 serve to retain the pins 29 and 30 in fixed relation to the members 31 and 32, respectively. At their lower ends each of the members 31 and 32 is provided with a boot portion 35 arranged to lie in flat surface engagement with one of the faces of the blade 27. A spring 36 which has its ends seated in pockets formed in the upper ends of the members 31 and 32 and which passes through a suitable opening in the plate 25 serves to urge the members 31 and 32 into the position in which the boots engage the blade 27 or the work passing between the boots and the blade. A guide pin 37 is secured to the blade 27 in any suitable way. It may be formed in two parts, one having internal screw threads cooperating with external screw threads on a reduced portion of the other half of the pin. The outer surface of the pin is smooth and of substantially frusto-conical form at each side of the blade 27. This is to facilitate cooperation with an open-

ing 38 provided in each of the boots forming part of the members 31 and 32. A slight clearance is provided between the wall of the opening 38 and the outer surface of the pin to permit free relative movement of the parts as the upper ends of the members 31 and 32 are pinched together for the introduction of the work blank. A portion of the wall of the opening 38 in each boot is removed or cut away to form a passage indicated at 39 (Fig. 4). This, in effect, forms a notch in the rearward edge of the boot. The arrangement is such that an upwardly extending projection 40 is provided in rear of the pin 37. The upper edge of projection 40 is smooth and rounded off to avoid danger of tearing the hosiery blank as the latter is drawn through the uncurler guide. The upper edge of the passage or cut out portion of the boot is preferably also provided with a slight projection 41, which extends downwardly around the surface of the guide pin 37 but this projection may, if desired, be eliminated and the upper edge of the passage may then be made substantially tangent to the opening 38 at its top. The upper end of projection 40 is preferably substantially in the horizontal plane containing the axis of the pin 37, although it may be slightly above or below such plane. The rearward edge of the boot 35 is preferably beveled as indicated at 42 to provide the boot 30 with a relatively sharp rearward edge.

In the operation of the machine a hosiery blank 43 (Fig. 6) will first be inserted in the uncurler guide, while the latter is in its loading position, i.e., that shown in Fig. X of the patent to Hacklander No. 2,131,007, granted September 20, 1938. At this time the guide will be midway between its operative and inoperative positions and will extend forwardly at an angle of about 45°. The boots 35 are shifted outwardly away from the stationary guide 27 by pinching together the upper ends of the members 31 and 32. The point 44 of the toe is slipped over the rearwardly extending portion of the stationary guide blade 27 and one of the selvage edges of the blanks is positioned along each face of the blade 27. Members 31 and 32 are then released so that the boots are permitted to grip the two edges of the blank against the face of the blade. The selvage edges of the blank curl over the rounded beveled upper edges 35a of the two boots. The machine is then started slowly and the guide is swung downwardly into the position indicated in the drawings and at the same time, the operator pulls the blank with her left hand to start the blank into the feed cups as the uncurler guide gets into operative position. In initiating the operation the point 44 of the toe of the blank is presented at the point of stitch formation indicated by the needle 16a. Now as the machine is set in operation at normal speed the blank will be advanced step by step by the feed cups 14 and 15 and a series of overedge stitches will be formed as the successive portions of the selvage edges are brought into the path of the needle. As the edge portions of the blank are drawn through the uncurler guide they are uncurled and held by the boots 35 in flattened condition against the faces of the blade 27. Normally in seaming the foot portion of the blank, up to the heel 45, and also in the seaming of the leg portion of the blank the latter is held by the operator slightly below the guide pin 37. However, in the formation of the heel the blank is lifted slightly into definite engagement with the guide pin in order to catch a greater

number of wales of the knit material in the seam. This is to offset and conceal the imperfections in the heel portion of the blank normally present as the blank comes from the knitting machine. It also insures a stronger seam which would otherwise be weakened by the imperfections in the blank. It is in the formation of the heel portion of the stocking that difficulties are particularly encountered in the use of the uncurler guides as heretofore constructed. This is due to the fact that the slightly lifted selvage edges tend to curl outwardly through the opening in the boots which receive the guide pin, and frequently these edges become wedged between the walls of the openings and the guide pin. When this occurs puckering or pleating of the seam takes place. The catching of the selvage edge in the manner explained occurs more frequently when loose ends of the knitting thread are present along the selvage edge and this difficulty may then arise even in the seaming of the foot and leg portions of the stocking. If one edge of the blank becomes caught in the manner indicated, while the other remains free, there is a tendency to pucker or pleat the one edge and not the other with the result that there is a mismatching of the edges.

The provision of the passage or cut out 39 in rear of the opening 38 has been found to eliminate the tendency of either of the selvage edges to hang up between the guide pin and the opening. Even though a portion of the edge may curl out temporarily between the lower edge of the guide pin 37 and the wall of the opening, the material is drawn freely out of the opening over the edge of the projection 40. Furthermore, the latter serves to impart a second uncurling action to the selvage edge as it is drawn along the projection, i. e. between the latter and the blade 27. This second uncurling action has been found to insure presentation of the selvage edges correctly to the point of stitch formation. The danger of including a curled portion of the edge in the seam is eliminated.

While an illustrative form of the invention has been disclosed in considerable detail, it will be understood that various changes may be made in the construction and arrangement of the several parts without departing from the general principles and scope of the invention as defined by the appended claims.

What I claim is:

1. An uncurler guide for hosiery seamers and the like which comprises a central support having a flat, vertically disposed work guiding surface, a spring urged presser member pivotally mounted on said support and having a surface cooperating with said surface of the support to assist in retaining and guiding the work, and a guide pin carried by said support and projecting laterally therefrom in the region of said surfaces, said presser member having an opening aligned with said guide pin and arranged to receive the same, said presser member having a portion of its edge removed to provide an externally communicating passage from said opening in a region which is at least in part above the horizontal diameter thereof and in rear of said guide pin.

2. An uncurler guide for hosiery seamers and the like which comprises a central support having a flat, vertically disposed work guiding surface, a spring urged presser member pivotally mounted on said support and having a surface cooperating with said surface of the support to assist in retaining and guiding the work, and a

guide pin carried by said support and projecting laterally therefrom, said presser member having an opening aligned with said guide pin and arranged to receive the same, said presser member having a portion of its edge removed to provide an externally communicating passage from said opening in a region in rear of said guide pin, the portion of said presser member defining the lower part of said opening being formed to provide a small upward projection in rear of said guide pin terminating adjacent the horizontal diameter of said opening.

3. An uncurler guide for hosiery seamers and the like which comprises a central support member, said member having a vertically disposed portion with flat work guiding surfaces on its opposite faces, a pair of presser elements pivotally mounted on said member and having surfaces adapted for engagement with said work guiding surfaces, means for yieldingly urging said surfaces on said presser elements against said work guiding surfaces, and a guide pin carried by said member and projecting laterally from said work guiding surfaces, each of said presser elements having an opening aligned with said guide pin adapted to receive the same freely and having a passage extending rearwardly from said opening.

4. An uncurler guide for hosiery seamers and the like which comprises a central support member, said member having a vertically disposed portion with flat work guiding surfaces on its opposite faces, a pair of presser elements pivotally mounted on said member and having surfaces adapted for engagement with said work guiding surfaces, means for yieldingly urging said surfaces on said presser elements against said work guiding surfaces, and a guide pin carried by said member and projecting laterally from said work guiding surfaces, each of said presser elements having an opening aligned with said guide pin adapted to receive the same freely and having a passage extending rearwardly from said opening, the lower edges of said opening and passage in each of said presser elements providing an upwardly and rearwardly extending surface arranged to guide and uncurl the corresponding edge of the work.

5. In a sewing machine having a pair of feed cups arranged for rotation about vertical axes and adapted to engage the opposite faces of a workpiece to feed the same and having stitch forming devices cooperating with the work in the region of the bite of said feed cups, the combination of an uncurler guide on the intake side of the feed cups which comprises a central support member, said member having a vertically disposed portion with flat work guiding surfaces on its opposite faces, a pair of presser elements pivotally mounted on said member and having surfaces adapted for engagement with said work guiding surfaces, said surfaces extending to a point adjacent the bite of said feed cups, means for yieldingly urging said surfaces on said presser elements against said work guiding surfaces, and a guide pin carried by said member and projecting laterally from said work guiding surfaces, each of said presser elements having an opening aligned with said guide pin adapted to receive the same freely and having a passage extending rearwardly from said opening slightly above the plane of the tops of the feed cups.

6. In a sewing machine having a pair of feed cups arranged for rotation about vertical axes and adapted to engage the opposite faces of a

workpiece to feed the same and having stitch forming devices cooperating with the work in the region of the bite of said feed cups, the combination of an uncurler guide on the intake side of the feed cups which comprises a central support member, said member having a vertically disposed portion with flat work guiding surfaces on its opposite faces, a pair of presser elements pivotally mounted on said member and having surfaces adapted for engagement with said work guiding surfaces, said surfaces extending to a point adjacent the bite of said feed cups, means for yieldingly urging said surfaces on said presser elements against said work guiding surfaces, and a guide pin carried by said member and projecting laterally from said work guiding surfaces slightly above the plane of the tops of the feed cups, each of said presser elements having an opening aligned with said guide pin adapted to receive the same freely and having a passage extending rearwardly from said opening slightly above the plane of the tops of the feed cups, the lower edge of said passage being disposed substantially in the horizontal plane containing the axis of said guide pin.

7. In a sewing machine having a pair of feed cups arranged for rotation about vertical axes and adapted to engage the opposite faces of a workpiece to feed the same and having stitch forming devices cooperating with the work in the region of the bite of said feed cups, the combination of an uncurler guide on the intake side of the feed cups which comprises a central support member, said member having a vertically disposed portion with flat work guiding surfaces on its opposite faces, a pair of presser elements pivotally mounted on said member and having surfaces adapted for engagement with said work guiding surfaces, said surfaces extending to a point adjacent the bite of said feed cups, means for yieldingly urging said surfaces on said presser elements against said work guiding surfaces, and a guide pin carried by said member and project-

ing laterally from said work guiding surfaces, each of said presser elements having an opening aligned with said guide pin adapted to receive the same freely and having a passage extending rearwardly from said opening, each of said presser elements having an upwardly and rearwardly extending surface in front of said guide pin arranged to guide and uncurl one of the upper edges of the work, and the lower edges of said opening and passage in each of said presser elements providing an upwardly and rearwardly extending surface arranged to guide and uncurl the corresponding edge of the work.

8. An uncurler guide for hosiery seamers and the like which comprises a central support member, said member having a vertically disposed portion with flat work guiding surfaces on its opposite faces, a pair of presser elements pivotally mounted on said member and having surfaces adapted for engagement with said work guiding surfaces, means for yieldingly urging said surfaces on said presser elements against said work guiding surfaces, and a guide pin carried by said member and projecting laterally from said work guiding surfaces, each of said presser elements having an opening aligned with said guide pin adapted to receive the same freely and having a passage extending rearwardly from said opening in a plane parallel with and adjacent the related work guiding surface of said support member.
